DESIGN FOR AN ELASTIC-TIRE TREAD.

● 54,624.

Specification for Design.

Patented Mar. 9, 1920.

Application filed November 6, 1919. Serial No. 336,186. Term of patent 14 years.

To all whom it may concern:

Be it known that I, LEWIS DE HOLCZER, a citizen of the United States, and a resident of Sioux City, in the county of Woodbury and State of Iowa, have invented a new, original, and ornamental Design for Elastic-Tire Treads, of which the following is a specification, reference being had to the accompanying drawing, forming a part thereof.

Referring to the illustrations, Figure 1 is a fragmentary plan of an elastic vehicle tire embodying my ornamental design; and

Fig. 2 is a transverse section thereof taken on the line 2—2 of Fig. 1.

I claim:

The ornamental design for an elastic tire tread as shown.

LEWIS DE HOLCZER.
